UNITED STATES PATENT OFFICE.

DANIEL SHERWOOD, OF LOWELL, MASSACHUSETTS.

HANDLE FOR WIRE-RIMMED ARTICLES.

SPECIFICATION forming part of Letters Patent No. 259,056, dated June 6, 1882.

Application filed April 12, 1882. (No model.)

To all whom it may concern:

Be it known that I, DANIEL SHERWOOD, of the city of Lowell, county of Middlesex, and State of Massachusetts, have invented a new and useful Handle for Wire-Rimmed Articles, of which the following is a specification.

My device relates to wire articles having a handle and a wire around the upper rim—such as handled strainers, small dippers, and other articles—and its objects are to provide a wire handle of great strength and stiffness, and of sufficient size to be readily grasped by the hand. I accomplish this object by the construction shown in the accompanying drawings, in which—

Figure 1 represents a plan, and Fig. 2 a side view.

A is the wire forming the rim of the article or holding its upper edge into form. This rim is formed of the bight or middle portion of the wire A, which is brought together at a and twisted into a stock or center post, a². This stock, however, when unsupported, has neither the stiffness nor, by itself, the size necessary to make a good and useful handle. I therefore connect with it the wire B, which is looped to form the outer end of the handle, and has its inner ends, b b, clasped around the wire A at point e, a short distance from the point a, while the ends a³ of the wire A are carried out at right angles to the center post, a², and clasped around the wire B at point c, after which, being dipped into the bath of melted tin, all places of juncture are firmly united. When at any time thereafter the handle is subject to flexure sidewise the tendency of such flexure will be to change the normal distances between the point e on one side of the stock and the point c on the other; but as the distance between the point a and the point c is small the wire A between these points will be practically unyielding, as will be the parts a³, because of

their limited length, so that the united parts act together as a truss, thus giving a much greater strength to resist flexure than would be the case if merely the aggregate of resistance of the separate wires to flexure was obtained. When subject to flexure in a perpendicular direction the ends a³ act as a fulcrum to support the middle portion of the wire B, and prevent any twisting of the ends b on the wire A, where they are clasped together, so that in all directions flexure will be greatly resisted and a strong and durable handle of very little weight of metal will be formed, which has no seams or openings in which dirt can find a place of deposit, and is especially adapted to all forms of utensils which have their upper rim partly formed of or supported by a strong wire, such as handled strainers, dippers, skimmers, egg-beaters, &c.

What I claim as new and of my invention is—

1. The combination of the rim-wire A, having its two parts twisted together at a² and separated into the two parts a³, which are extended at right angles to the twisted portion and clasped around the strengthening-wire B, with such wire B bent to form a loop, and having its ends b b clasped around the wire A near the twisted portion, substantially as described.

2. A handle for articles having a wire-supported rim formed of portions of such wire twisted together and extending out from such rim a part of the length of such handle and then separated to form supports to a wire-loop whose ends are clasped to the rim portion of such rim-wire, and which forms part of the handle, substantially as described.

DANIEL SHERWOOD.
